UNITED STATES PATENT OFFICE

ANTHONY CAGGIANO, OF SPRINGFIELD, MASSACHUSETTS

TEMPLATE FOR SPLITTING LEATHER SOLES

Application filed June 6, 1931. Serial No. 542,660.

My invention relates to improvements in templates for splitting leather soles which are usually used in repairing shoes.

An object of my invention is to provide a template to be used in co-operation with a leather splitting machine, so that, by using the template, the desired thickness and surface of the sole will be removed without slitting the sole over its entire area. It is the practice, at the present time, to run a sole through a splitting machine when the sole is thicker than required for the repair work at hand. This reduces the thickness of the sole, but at the expense of the wearing surface, as well as at the edges. In other words, the splitting machine removes a layer of leather from the sole over its entire area. By the use of my invention, this objection is overcome, and a strip of the sole only is removed, where desired, leaving the remainder of the sole of full thickness.

In the embodiment of my invention illustrated in the accompanying drawing, a template is shown which in use permits the removal of a strip of leather around, or along the marginal edge of a sole while retaining the full thickness of the leather at the center of the sole, or that part normally located under the ball of the foot, and, therefore, in a position to receive the most wear. However, I do not confine myself to this shape, as it will be readily understood that various shapes of templates may be used, depending upon that portion of the sole desired to be removed and that portion to be retained, in any particular case.

Other objects and advantages of my invention will appear in the specification, accompanying drawing, and appended claim.

In the accompanying drawing:

Fig. 1 is a plan view illustrating a template placed upon a leather sole ready for insertion in a splitting machine.

Fig. 2 is a partial, sectional view illustrating the displacement of the leather by the template, forcing down the portions of the leather under the template into position for engagement with the knife of the splitting machine.

Fig. 3 is a diagrammatic view illustrating

the leather sole and template as they are engaged in the splitting machine.

Fig. 4 is a sectional view of a leather sole, after its passage with the template through the splitting machine, and

Fig. 5 is a plan view illustrating the strip of leather removed from the sole by the splitter.

Referring now to the drawing in detail, in which like numerals refer to like parts throughout:

The gage 1, of some thin, transparent substance, preferably celluloid, is formed with the centrally disposed opening 2, and is placed in the desired position over the leather sole 3, and the template 1 and sole are then inserted between the revolving rolls 4 of a stripping machine. The rolls 4 exert pressure upon the sole 3 and template 1, thereby causing the template, where it is in engagement with the sole 3, to force the marginal portions 5 of the sole 3 downward into engagement with the knife 6. Thus, as the sole 3 is forced through the rolls 4 into engagement with the knife 6, the marginal portion 5 of the sole leather are sheared off, while the centrally disposed portion 7 of the sole 3 is displaced upward into the opening 2 in the template 1 by reason of the pressure of the rolls 4, rides freely over the knife 6, thereby retaining its full thickness, as illustrated in Fig. 4 at 3'. In Fig. 4, is illustrated a cross section of a leather sole 3, after passing through a slitter with one of the templates and illustrating the full thickness at 3' and the thinned edges 8. Fig. 5 illustrates the strip of leather 5 removed by the knife 6 from the marginal edge of a leather sole.

It will thus be understood that I have provided a means for removing any desired, restricted area from a leather sole, without disturbing the thickness of the remaining area of the sole. It is also within the scope of my invention that templates of different thickness may be employed, whereby the removed portion 5 will, of course, be different. The advantage of using a transparent template is to assist the user in locating the same on a piece of sole leather.

What I claim is:—

As an article of manufacture, a template
for shoe soles comprising a sheet of thin
transparent material, as celluloid, of a shape
and size corresponding to the shape and size
of a leather sole and formed with a centrally
disposed opening whose periphery is approxi-
mately parallel to the outer edge or periphery
of said template.

In testimony whereof, I hereunto affix my
signature.

ANTHONY CAGGIANO.
